UNITED STATES PATENT OFFICE

JOHN P. Saporiti, OF BARRE, VERMONT

POLISHING APPARATUS

Application filed August 6, 1923. Serial No. 655,992.

The object of my said invention is the provision of a polishing apparatus constructed with a view to use with facility in expeditiously and thoroughly polishing heavy work 5 and wide surfaces such as heavy and large stones.

To the attainment of the foregoing, the invention consists in the improvement as hereinafter described and definitely claimed.

10 In the accompanying drawings, forming part of this specification:—

Figure 1 is a view partly in front elevation and partly in vertical longitudinal section showing one type of apparatus constructed in 15 accordance with my invention.

Figure 2 is an end elevation of the same.

Figure 3 is an enlarged detail vertical section of one of the polishers, taken in the plane indicated by the line 3—3 of Figure 1, 20 looking toward the right.

Figure 4 is an enlarged plan view of one of the polishing wheels or polishers.

Figure 5 is a horizontal section taken in the plane indicated by the line 5—5 of Figure 25 3, looking downwardly.

Figures 5^a and 5^b are views of details hereinafter explicitly referred to.

Figure 5^c is a section showing a slight modification.

30 Figures 6, 7, 8, 9, 10, 11 and 12 are views illustrative of modifications hereinafter referred to in detail; Figure 8 being a detail section on the line 8—8 of Figure 7, and Figure 12 being a detail vertical section on the line 12—12 of Figure 11.

Similar numerals designate corresponding parts in Figures 1 to 5^b to which reference will first be made.

40 In accordance with my invention as shown in Figures 1 to 5^a, I employ a plurality of track rails 1 in parallelism, upon which is movable a car 2 on which is arranged a stone or stones 3 to be polished.

45 Any appropriate means may be employed for the movement of the car and stone or stones thereon, although I prefer to employ for the purpose a rope or cable 4, Figure 2, connected at 5 and 6 to the car to be actuated, 50 and associated with drums 8 on a shaft 8^a to

be driven by appropriate means such as the electric motor 8^b shown in Figure 1.

Fixedly secured in concrete bases 9 at opposite sides of the group of rails 1 are uprights 10 appropriately braced at 11. Fixed 55 to and extending at right angles between the uprights 10 are lower and upper frame beams 12 of which four are employed. It will be observed that the beams 12 rest above the carriage 2 and the stone or stones thereon and at right angles to the line of movement of said carriage and stone or stones.

Arranged above the stone or stones to be polished and in association with the beams 12 are polishing units of which four are illustrated although it is within the purview of my invention to employ any desired number of polishing units. The said polishing units are identical in construction and therefore a detailed description of the one shown in 70 Figures 3, 4, 5, 5^a and 5^b, will suffice to impart a definite understanding of all. By reference to Figures 3, 4, 5, 5^a and 5^b it will be understood that the unit therein illustrated comprises among other elements a polisher or polishing wheel 13. Superimposed on the said wheel or polisher 13 which is of any material compatible with its purpose is an annular weight 13^a which is preferably, though not necessarily, employed with a view 75 to holding the wheel or polisher down to its work. The said polisher or wheel 13 is provided at its underside with a central opening 14 in communication with which are ducts 14^a, Figure 5, through which fluid carrying abrasive substance may be fed to the opening.

It will be noted that the polisher or wheel 13 is provided at its underside with scroll-like channels 15, preferably of the type best shown in Figures 3 and 4, the purpose of 80 which is to conduct fluid and abrasive substance outwardly from the central opening 14 to the outer portion of the polisher with a view to utilizing the fluid and abrasive substance to the best advantage incident to the 85 work of the polisher or wheel on the stone or stones to be polished. As illustrated I prefer to detachably connect by screws or other means the walls 15^a of the channels 15 to the heads of the wheels or polishers 13 so that 90 100

said walls 15^x may be replaced when worn. The polisher or wheel 13 is fixed at 16 to an upright shaft 17 which extends between the pairs of beams 12, Figure 3, and has fixed on its upper portion a band pulley 18. The shaft 17 extends through and is carried by a housing 17^x which is arranged and movable bodily between the beams 12, anti-friction means such as balls 19 being interposed between the 10 housing and the beams 12 so that the housing can be moved to and fro relative to the beams 12 with but a minimum amount of friction. Surrounding the shaft 17 is a flanged sleeve 17^a, the upper portion of the sleeve being journaled in the housing 17^x, and the flange abutting against the lower end of the said housing 17^x. Loosely arranged on the sleeve is a washer 17^b, between which and the said flange are interposed anti-friction balls 17^c. At 20 17^d is a nut that is threaded on the lower end of the sleeve 17^a, and between the said nut 17^d and the loose washer 17^b is interposed a spring 17^A which loosely surrounds the lower portion of the sleeve 17^a. Manifestly when 25 the nut 17^d is adjusted the spring 17^A can be compressed and secured in compressed state about the sleeve 17^a so as to take the pressure of the spring off the polisher or wheel 13. When, however, the nut 17^d is turned off the 30 sleeve 17^a and permitted to bear on the collar 17^e which loosely surrounds the shaft 17, the polisher or wheel 13 will be subject to the pressure of the said spring. The collar 17^e is separated by anti-friction balls, Figure 3, 35 from the portion of the wheel or polisher to which the shaft 17 is connected by a thread as illustrated. When desired the spring 17^A may be supplemented by a weight 13^a such as before described. The walls 15^x of the polishers 40 are preferably formed of soft iron to afford the best results, and hence it is materially desirable to have the said walls 15^x detachable from the heads of the polishers 13, which heads or covers are preferably of soft steel.

45 In lieu of the rigid connection between polisher 13 and shaft 17 as shown in Figure 3, a universal connection 16^x may be employed between the said elements as shown in Figure 5^e, so as to enable the polisher to accommodate itself to the face of the stone that is being polished.

50 It will be understood from the foregoing that the battery of polishing units are movable between the beams 12 in opposite directions lengthwise of the said beams 12. The several housings 17^x are connected together by rods 25, Figure 1, and hence it will be understood that all of the polishing wheels will be moved to and fro in concert, and this 55 without interfering with the rotation of the polishing wheels about their axes. The several band pulleys 18 are connected by bands 18^a with long pulleys 18^b, Figure 1, the said pulleys 18^b being fixed on a shaft 18^c, Figures 60 1 and 2. The said shaft 18^c is equipped

with a band pulley 18^d for the connection of the shaft with a motor not illustrated. At 18^e and 18^f are short shafts connected by pulleys and bands with the shaft 18^c, and at 18^g and 18^h are rack bars each of which is connected to an adjacent housing 17^x, as indicated by 18ⁱ, Figure 1. Meshed with the rack bar 18^g is a mutilated gear 30, and intermeshed with the rack bar 18^h is a mutilated gear 31. Fixed with respect to the gear 30 70 are disks 32, Figures 1 and 2, and fixed with respect to the gear 31 are similar disks 33. These disks 32 and 33 are connected through the medium of equalizing rods 20 so as to assure the gears 30 and 31 moving in concert. The shaft 18^c is connected with the adjacent gear 31 by a band 35 and appropriate pulleys. It will also be noticed by comparison of Figures 1 and 2, that both shafts 18^e and 18^f are connected with the shaft 18^c by bands 36 80 and appropriate pulleys. In virtue of this construction it will be apparent that incident to the operation of the apparatus the battery of polishing units will be moved to and fro longitudinally of the beams 12, the movement 85 of the battery of polishing units in one direction being effected by the cooperating gear 30 and rack bar 18^g, and the movement of the battery of the polishing units in the other direction being effected by cooperation between rack bar 18^h and the gear 31, it being understood in this connection that when one of the said gears is operating to move the battery of polishing units in one direction, the smooth portion of the other gear will be presented to its complementary rack bar so as 90 not to interfere with said movement.

95 It will be manifest from the foregoing, that during the operation of the embodiments thus far described in detail, the carriage 2 will be reciprocated or moved to and fro on the rails 1, the motor 8^b being preferably a reversible motor characterized by a separately excited field. It will also be understood that during the said movements of the carriage below and at right angles to the beams 12, the polishers 13 will be rotated about their axes on the stone, and at the same time the polishers will be moved together crosswise of the path 100 of movement of the carriage and the stone so that all portions of the surface of the stone will be polished, and this thoroughly and expeditiously, and with but little attention on the part of an attendant or attendants.

105 In the modification shown in Figure 6, I employ in lieu of the gears 30 and 31 bevel gears, one of said bevel gears being shown in Figure 6, and being numbered 31^a. The bevel gears 31^a are driven from the shafts 18^e and 18^f and are meshed with bevel gears 18^m, and the said bevel gears 18^m are connected by rods 18ⁿ with adjacent housings 17^x. Manifestly with the driving connections such 110 as shown in Figure 6, at opposite ends of the 120

beams 12, the battery of polishing units will be moved to and fro lengthwise of the beams 12 in the manner before described.

In the modification shown in Figures 7, 8, 9 and 10, the stone to be polished remains stationary, while the polishing apparatus is moved as a whole crosswise of the stone, and the polishing units are moved to and fro in the frame of the apparatus and at right angles to the line of movement of the polishing apparatus as a whole, the polishing units being rotated about their axes incident to the said movements at right angles to each other. In said modification, Figures 7-10, the polishing units are similar to those before described, and the means shown in Figure 6, and before described is preferably employed to move the polishing units together lengthwise of the frame and relative to the frame. The frame carrying the polishing units is moved at right angles to the line of movement just indicated on a pedestal, the frame being numbered 12^a and the pedestal being numbered 12^b, and said frame and pedestal being relatively arranged as best shown in Figures 7 and 8. The frame 12^a is provided with racks 50, and intermeshed with the said racks are spur gears 51, fixed on a shaft which also carries a spur gear 52. At 53 is an electric motor preferably of the reversible type before indicated, and between the said electric motor and the gear 52 is a reducing gearing 54. Manifestly when the motor 53 is actuated the frame 12^a will be moved as a unit to and fro relative to the pedestal 12^b. At 55 is a motor on a carriage 56, said carriage being superimposed and movable on a support 57. Intermediate of the motor 55 and the apparatus is a driving connection 58 to rotate the polishing units about their axes, and also intermediate of the said motor 55 and the apparatus is a driving connection 59 to rotate the gears 18^m and bring about reciprocation of the connected polishing units in a line at right angles to the line in which the apparatus as a whole is moved to and fro. When desired the motor may be dispensed with and a driving connection such as shown in Figure 10 may be applied directly to the shaft that carries the pinions 51; also, in some cases the said shaft may be provided with a crank 52^x as shown in Figure 9 for the movement of the frame 12^a by hand.

In the modification shown in Figures 11 and 12, the stone 3^a to be polished remains stationary, and the frame 12^t which carries the rotary polishing units is moved in one direction through the medium of a threaded shaft 70 and nuts 71, and is moved in a line at right angles to said direction by a threaded shaft 72 and nuts 73, appropriate power being applied to said shafts in any manner compatible with the purpose of my invention. It will also be observed that provision is made in the said embodiments, Figures 11 and 12,

for the power raising and lowering of the frame 12^t, the said raising and lowering means as shown comprising upright threaded shafts 80 threaded through the frame 12^t for the raising and lowering thereof, and a driving connection 81 connected by telescopic means with the said shafts 80.

In all of the embodiments of my invention hereinbefore shown and described, it will be understood that provision is made for the rotation of the polishing units about their axes, and for the movement of the group of polishing units relative to the stone that is being acted upon so as to assure the polishing of all of the surface of the stone.

I have entered into a detailed description of the construction and relative arrangement of the parts embraced in the present and preferred embodiments of my invention in order to impart a full, clear and exact understanding of the said embodiments. I do not desire, however, to be understood as confining myself to the specific construction and relative arrangement of parts inasmuch as in the future practice of the invention various changes and modifications may be made such as fall within the scope of my invention as defined in my appended claims.

Having described my invention, what I claim and desire to secure by Letters Patent, is:

1. In a polishing apparatus the combination of a frame, a housing arranged against vertical movement in the frame, a sleeve journaled in the housing and having a flange intermediate of its ends abutting against the lower end of the housing, a shaft journaled in the sleeve and housing, and a polisher connected to the lower end of the said shaft, a nut surrounding said shaft and adapted in one position to freely rest against the upper surface of the polisher, a coiled spring surrounding the sleeve and interposed between the flange and the nut to yieldingly urge the polisher against the work, said nut being adapted to be threaded on the end of the sleeve to confine the spring between it and the flange thereon so that the spring is restrained from yieldingly acting upon the said polisher.

2. In a polishing apparatus, the combination of a frame, a housing arranged against vertical movement in the frame, a sleeve journaled in the housing and having a flange intermediate of its ends, a shaft journaled in the sleeve and housing, and a polisher connected to the lower end of the shaft, a nut surrounding said shaft and adapted in one position to freely rest against the upper surface of the polisher, a spring surrounding the sleeve and interposed between the flange and the nut to urge the polisher against the work, said nut also being adapted to be threaded on the end of said sleeve to confine the spring between it and the flange thereon to restrain

it from acting upon the polisher, anti-friction means between said spring and the flange on the sleeve, and a collar loosely surrounding the shaft and separated by anti-friction means from the polisher to afford a bearing for the nut when said nut is disconnected from the sleeve.

3. In a polishing apparatus, the combination of a frame having two upper rails spaced horizontally from each other, two lower rails similarly spaced from each other and also spaced from the upper rails, housings arranged in said frame and movable laterally therein and having intermediate enlargements interposed between the upper rails and the lower rails, anti-friction means interposed between the housings and the frame rails, and means for connecting said housings whereby they are movable together as a unit, means for moving the connected housings to and fro longitudinally of the frame, sleeves journaled in the housings and having flanges opposed to the lower ends of the housings, nuts detachably connected to the lower ends of the sleeves, coil springs surrounding the sleeves and interposed between the flanges thereof and said nuts, upright shafts journaled in the sleeves and housings, means connected with the shaft above the housings for rotating the shafts about the axes, and polishers connected with the lower ends of the shaft adapted to be contacted by the nuts when said nuts are disconnected from the sleeves.

35 4. In a polishing apparatus, the combination of a frame having two upper rails spaced horizontally from each other, two lower rails similarly spaced from each other and also from the upper rails, housings having intermediate portions interposed between the upper rails and lower rails whereby said housings are held against vertical movement relative to the frame, said housings connected together and movable horizontally in the frame, shafts journaled in the housings, polishers connected with the lower portions of said shafts, springs surrounding said shafts and interposed between the lower ends of the housings and the polishers and adapted to hold the polishers yieldingly to their work, pulleys on the upper portions of the shafts, longitudinal rotary drive means, and belts connecting said longitudinal drive means and the pulleys to move the housings to and fro 55 including the short shafts connected with said longitudinal drive means, pulleys on said shafts and gear shifted rack bars to operate the housings.

In testimony whereof I affix my signature.
JOHN P. SAPORITI.
